UNITED STATES PATENT OFFICE.

EDWIN J. ARMSTRONG, OF ERIE, PENNSYLVANIA, ASSIGNOR OF ONE-HALF TO
ARTHUR C. VICARY, OF ERIE, PENNSYLVANIA.

POWER SHOVEL.

Application filed September 20, 1921. Serial No. 501,903.

To all whom it may concern.

Be it known that I, EDWIN J. ARMSTRONG, a citizen of the United States, residing at Erie, in the county of Erie and State of Pennsylvania, have invented new and useful Improvements in Power Shovels, of which the following is a specification.

This invention is designed to handle the slack latch line operating the latch of a dipper of a power shovel. This latch line must be entirely free as the dipper is retracted in order that the latch may surely lock the cover. On the other hand as the dipper is elevated and is in position to be dumped it is desirable to have this line with as little slack as possible in order that the operator may accomplish the purpose with the greatest convenience and this is particularly advantageous in that the pulling of the latch line ordinarily should be accomplished with one hand.

The invention is illustrated in the accompanying drawings as follows:—

Fig. 1 shows a side elevation of the power shovel with the device in place with the dipper retracted.

Fig. 2 shows a similar elevation with the dipper in its upper position preparatory to tripping the latch.

Fig. 3 a detail view of the trip lever.

Fig. 4 a front elevation of the trip lever.

Fig. 5 a section through the crowding shaft and winding spool.

1 marks the frame, 2 the wheels, 3 the turn table, 4 the boom, 5 the dipper, 6 the dipper stick, 7 a rack on the dipper stick, 8 the crowding gears operating on the rack 7, 8^a a shaft on which the crowding gears are mounted, and 9 a gear on the shaft 8^a actuated from the crowding engine shaft 10, the shaft 10 being in the ordinary crank shaft of the crowding engine 11. The hoisting line 12 is secured to the dipper carried over the sheave 13 at the upper end of the boom and operated on the usual drum 14. The dipper is provided with the usual swinging bottom 15 pivotally mounted at 16, the bottom of the dipper 17 having a latch opening 18. A latch 19 is slidably mounted in the lugs 20 on the movable bottom and as the latch is pulled back or upwardly the bottom is released thus permitting the dipper to dump in the usual man-

ner. When the dipper is retracted to the position shown in Fig. 1 the bottom swings 55 to shut position and the latch should be free to snap into the opening 18 so as to lock the bottom in closed position. These parts are, or may be, of the usual construction.

A pull chain 21 extends from the latch to a lever 22. The lever 22 is pivoted at 23 on the dipper stick 6. A latch line 24 extends from the lever 22 around a sheave 25 to a spool 8^b secured on the end of the 65 crowding shaft 8^a. The sheave 25 is mounted between the arms of a swinging lever 26 pivotally mounted on a pin 27 carried by a bracket 28, the bracket 28 being secured to the boom 4. A guard plate 29 is arranged 70 around the sheave and an eye 30 is secured to the plate 29 and the pull line 31 extends from the eye to a point in the power shovel in position to be grasped by the operator and pulled. In the operation of the device 75 when the dipper is retracted the spool is rotated with a movement of the dipper stick through the action of the crowding engine and the latch line 24 is wound up to correspond approximately to the movement of 80 the dipper stick. As the dipper stick is moved outwardly the spool is rotated to unwind the latch line so that the latch line may follow the dipper stick without great change in the slack. The position of the 85 lever 26, however, is varied slightly and its action on the latch line varies considerably. When the dipper is retracted to the position shown in Fig. 1 the engagement of the sheave 25 with the latch line does not affect 90 the slack in this line to any great extent. When, however, the dipper is thrust forward the latch line is carried around the sheave, the span from the spool to the sheave being approximately at right angles to the 95 span from the sheave to the lever 22. The weight of the lever 26, however, is not sufficient in itself to pull the latch. It does, however, make the latch line and pull chain taut so that the initial movement of the 100 latch line through the action of the pull line trips the dipper. Further the position of the lever 26 with relation to the pull line and span extending from the sheave 25 to the lever 22 is such that approximately the 105 entire pulling effort on the pull line is trans-

mitted to the latch line thus making the tripping of the latch convenient and at the same time requiring little effort.

What I claim as new is:—

- 5 1. In a power shovel, the combination of a dipper; a swinging bottom for the dipper; a latch for the bottom; a dipper stick; a spool rotating as the dipper stick moves; a latch line operating on the latch and winding on the spool as the dipper stick is drawn in; a pull line; and means actuated by the pull line and acting on the latch line, said means increasing the slack of the latch line as the dipper is retracted and decreasing the slack as the dipper stick is swung outwardly. 55
- 10 2. In a power shovel, the combination of a dipper; a swinging bottom for the dipper; a latch for the bottom; a dipper stick; a spool rotating as the dipper stick moves; a latch line operating on the latch and winding on the spool as the dipper stick is drawn in; a pull line; and means actuated by the pull line and acting on the latch line, said means increasing the slack of the latch line 60 as the dipper is retracted and decreasing the slack as the dipper stick is swung outwardly, comprising a downwardly hanging swinging lever with its free end engaging the latch line. 65
- 15 3. In a power shovel, the combination of a dipper; a swinging bottom for the dipper; a latch for the bottom; a dipper stick; a spool rotating as the dipper stick moves; a latch line operating on the latch and winding on the spool as the dipper stick is drawn in; a pull line; and means actuated by the pull line and acting on the latch line, said means increasing the slack of the latch line 70 as the dipper is retracted and decreasing the slack as the dipper stick is swung outwardly, comprising a weight varying its action on the latch line as the dipper stick is swung. 75
- 20 4. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 80 acting on the latch line, said means increasing the slack of the latch line as the dipper is retracted and decreasing the slack as the dipper stick is swung outwardly. 85
- 25 5. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 90 acting on the latch line, said means increasing the slack of the latch line as the dipper is retracted and decreasing the slack as the dipper stick is swung outwardly. 95
- 30 6. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 95
- 35 7. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 95
- 40 8. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 95
- 45 9. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 95
- 50 10. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 95

means increasing the slack of the latch line as the dipper is retracted and decreasing the slack as the dipper stick is swung outwardly, comprising a swinging lever with a sheave at its free end engaging the latch line.

5. In a power shovel, the combination of a dipper; a swinging bottom for the dipper; a latch for the bottom; a dipper stick; a spool rotating as the dipper stick moves; a latch line operating on the latch and winding on the spool as the dipper stick is drawn in; a pull line; and means actuated by the pull line and acting on the latch line, said means increasing the slack of the latch line 65 as the dipper is retracted and decreasing the slack as the dipper stick is swung outwardly, comprising a downwardly hanging swinging lever with its free end engaging the latch line. 70

6. In a power shovel, the combination of a dipper; a swinging bottom for the dipper; a latch for the bottom; a dipper stick; a crowding shaft for the dipper stick; a spool mounted on the crowding shaft; a latch line operating on the latch and winding on the spool as the stick is drawn in; a pull line; and means actuated by the pull line and 75 acting on the latch line, said means increasing the slack of the latch line as the dipper is retracted and decreasing the slack as the dipper stick is swung outwardly. 80

7. In a power shovel, the combination of a dipper; a swinging bottom for the dipper; a latch for the bottom; a dipper stick; a spool mounted on the crowding shaft; a latch line operating on the latch and winding on the spool as the stick is drawn in; a pull line; and means actuated by the pull line and 85 acting on the latch line, said means increasing the slack of the latch line as the dipper is retracted and decreasing the slack as the dipper stick is swung outwardly. 90

In testimony whereof I have hereunto set my hand.

EDWIN J. ARMSTRONG.
